CLAIM

The ornamental design for an airspeed device, as shown and described.

DESCRIPTION

FIG. 1 is a top front perspective view of an airspeed device showing the new design.

FIG. 2 is a front view thereof.

FIG. 3 is a rear view thereof.

FIG. 4 is a side view thereof.

FIG. 5 is a side view thereof, opposite of the side view of FIG. 4.

FIG. 6 is a top view thereof; and,

FIG. 7 is a bottom view thereof.

The evenly spaced broken lines in the drawings depict portions of the airspeed device that form no part of the claimed design.

1 Claim, 6 Drawing Sheets(56)
